UNITED STATES PATENT OFFICE.

ROBERT L. DAVIS, OF WILKINSBURG, PENNSYLVANIA, ASSIGNOR TO WESTINGHOUSE ELECTRIC & MANUFACTURING COMPANY, A CORPORATION OF PENNSYLVANIA.

RADIO SYSTEM.

Application filed June 10, 1925. Serial No. 36,101.

My invention relates to radio signalling systems, and particularly to features of keying systems therefor.

An object of my invention is to provide 5 means whereby triode vacuum tubes in a radio signalling system are protected from excess voltages.

Another object of my invention is to provide 10 a triode vacuum tube radio signalling system, a rectifier and filter combination adapted to co-operate therewith, and keying means having auxiliary means for preventing the development of undesirably high potentials.

Another object of my invention is to provide 15 a key having an auxiliary contact member connected across the terminals of a filter inductance whereby the latter may be short-circuited.

In the prior construction and operation 20 of radio signalling systems, it has been found convenient to generate radio frequency currents by means of vacuum-tube oscillators, and to interrupt the oscillations by suitable keying means. For the generation 25 of substantial amounts of radio-frequency power, it has, however, been found necessary to employ relatively high-voltage currents, which are most easily obtained by

30 thermionic rectifier devices. Such rectifier devices, however, furnish a pulsating current, which pulsations cause a modulation of the radio-frequency output. This modulation has been found objectionable for signalling 35 systems where it is desired to use the pure heterodyne reception method. In order to avoid such modulation, it has been found desirable to connect a filter system between the oscillation generator and the rectifier 40 device to smooth out the current pulsations in the rectifier output.

Keying has been effected by making the 45 grid of the oscillation generator more strongly negative, which may be accomplished by the application of a definite negative grid bias, or by open-circuiting a grid leak between the grid and the cathode. In either instance, the conductivity of the tube is markedly decreased very suddenly and the 50 sudden reduction of current through the filter choke results in the development of very high instantaneous potentials.

In many instances it is not convenient to 55 employ tubes which will withstand the excess voltages. This is especially the case

when it is desired to send pure, continuous wave signals instead of the interrupted, continuous wave signals described in the previously-mentioned copending application.

My invention provides means for preventing 60 the application of these sudden high potentials upon the oscillation generator during the operation of keying.

Other objects and structural details of my 65 invention will be apparent from the following description when read in connection with the accompanying drawing, wherein

Figure 1 shows a preferred embodiment of my invention, and

Fig. 2 shows an alternative embodiment. 70

Referring to the drawing, an oscillation radiator comprises an aerial 1, a tuning inductance 2, and a counterpoise 3. The radiator is connected to an oscillation generator comprising a triode 4 connected to a local 75 oscillatory circuit consisting of an inductance 5 and a condenser 6 by means of a plate circuit connection 7, a cathode connection 8 and a grid connection 9 through a stopping condenser 11. A grid leak 12 has 80 one terminal connected to the grid circuit 9. A key 14 has a bar that is connected to the cathode circuit 15 of the triode 4 and the front contact of which is connected to the other terminal of the grid leak 12. 85

A rectifier system comprises thermionic 90 rectifiers 16 and 17 that are connected to a filament-heating transformer 18 and a plate current transformer 19. Both transformers are supplied by a source of alternating current 21.

A filter system is connected between the 95 oscillation generating system and the rectifier system. This filter consists of an inductance 22 and capacitances 23, 24 and 25 connected in a well-known manner.

Referring to Fig. 1, the output terminal 100 of the filter inductance 22 is connected to the cathode circuit 15 to which the key 14 is also connected. The key 14 has a back contact which is adapted to close simultaneously with, or slightly before, the opening of the front contact. The back contact is connected to the in-put terminal of the filter inductance 22.

In the operation of the system, the key 14 105 may be depressed and upon energization of the rectifiers and the filament of the oscillation generator, oscillations at the resonant frequency will be developed and radiated. The 110

key may be alternately opened and closed to interrupt the trains of oscillations into the desired signal code. With the key 14 depressed, a suitable grid bias for satisfactory operation is developed under the control of the grid leak 12.

Upon opening the key, the grid circuit through the leak 12 is opened and the grid immediately becomes more negative to a degree sufficient to prevent the development of oscillations by the triode 4, and to reduce the current traversing the tube. Simultaneously, the increase in voltage which tends to occur across the terminals of the inductance 22, due to the great increase in impedance of the triode 4, is by-passed through the back contact of the key 14 and, therefore, only the normal voltage produced by the rectifier 19 is impressed upon the triode 4. This is an unfiltered voltage with the usual fluctuation in it but, since the triode is not oscillating, the fluctuation is not objectionable.

Upon reclosing the key 14, the shunt is removed from the filter inductance 22 and it resumes its activity and simultaneously the charge upon the grid is reduced from a strongly negative value to that negative value adapted to most suitable operation, as determined by the value of the grid leak resistance 12.

The foregoing preferred embodiment is suitable for small and medium powers. In the event, however, that a very high power system is employed, the energy by-passed from the inductance 22 through the back contact of the key 14, may be sufficiently great to cause troublesome arcing of the key contacts and it may tend to produce local low-frequency surges.

This may be avoided by the embodiment shown in Fig. 2, in which a resistor 26 is connected in series with the back contact of the key 14 for the purpose of dissipating the energy from the inductance 22. A large condenser 27 may also be advantageously added in certain instances where it is desired to bypass only the inductive component of the coil 22 and not to bypass the current produced by the ohmic drop in the coil.

In the event that still more electrical energy is to be translated in the apparatus, the system of Fig. 2 may prove insufficient for complete protection of the back contact of the key 14. Additional protection to these contact members may be obtained by shunting them with a condenser in series with a suitable resistance.

In the event that it is desired to connect the filter inductance in the ungrounded side 60 of the circuit, the same results as are obtained by the previously described constructions may be obtained by adding an insulated winding to the core along side of the coil of the filter inductance 22 and connecting its 65 terminals to the back contact of the key 14.

The closure of the contacts thus closes the circuit in the damper winding which absorbs all of the energy due to the discharge of the magnetic field in the core of the filter inductance 22 which otherwise would produce an undesirably high voltage upon the triode 4.

By the systems, as described, I am enabled to operate a triode oscillation generator in series with a rectifier and filter choke at its maximum allowable voltage without danger of imposing thereon momentary excess surge voltages from the operation of keying.

While I have shown several specific embodiments of my invention in the accompanying drawing and description, it is capable of other modifications therefrom without departing from the spirit thereof, and it is desired, therefore, that only such limitations shall be imposed thereon as are indicated by the prior art or by the appended claims.

I claim as my invention:

1. A radio signalling system, comprising an oscillation generating means, a source of fluctuating current connected thereto, a filter means connected therebetween, and means for simultaneously causing the cessation of oscillations in said generator and the short-circuiting of an element of said filter means. 95

2. A radio signalling system, comprising an oscillation generating means, a source of fluctuating current connected thereto, a filter means connected therebetween, and a keying means having a back contact member connected to said current source and a front contact member connected to said oscillation generating means. 100

3. A radio signalling system, comprising an oscillation generating means, a source of energy therefor comprising an alternating current generator and a rectifier, a filter system connected therebetween, a keying means associated with said generator for interrupting said oscillations, and means associated with said key for preventing the development of excess voltages in said filter during non-oscillating periods. 110

4. A radio signalling system, comprising an oscillation generating means, an energy supply therefor comprising a dynamo and rectifier, filter means comprising an inductance, connected therebetween, and a keying means, associated with said generator, and having a back contact member adapted to short-circuit said inductance and a front contact member connected to said oscillation generating means. 115

5. A radio signalling system, comprising a triode oscillation generator, means for causing the grid thereof to become sufficiently negative in potential to stop the generation of oscillations, an inductance in the supply circuit of said generator, and means associated with said first-mentioned means for pre- 125

venting the development of excess voltage in said inductance.

6. A radio signalling system, comprising a triode oscillation generator, a plate current supply comprising a generator and rectifier device and connected thereto, filter means comprising associated inductance and capacitance elements connected therebetween, a grid condenser and grid leak connected to the grid of said triode, and a key having both front and back contact members the front contact member being connected to said grid leak and the back contact member being connected to said filter system.
- 10 7. A radio signalling system, comprising a triode oscillation generator, a plate current supply comprising a generator and rectifier device and connected thereto, filter means

comprising associated inductance and capacitance elements connected therebetween, a 20 grid condenser and grid leak connected to the grid of said triode, and a key having both front and back contact member, the front contact member being connected to said grid leak and the back contact member 25 being connected to said filter system whereby in one position, the key opens the grid leak circuit and closes a circuit in shunt to the inductance in said filter means, and in the other position, closes the grid leak circuit, 30 and opens the shunt circuit for the filter.

In testimony whereof, I have hereunto subscribed my name this 21st day of May, 1925.

ROBERT L. DAVIS.
